(57) **CLAIM**

The ornamental design for a canister as shown and described.

DESCRIPTION

FIG. 1 is a side and bottom perspective view of a first and third embodiment of a canister, showing a cap portion independent of the canister to show aspects of the design not visible when combined;

FIG. 2 is a front elevation view of a first, second, third and fourth embodiment of a canister, showing a cap portion independent of the canister, wherein the back, left, and right views are identical;

FIG. 3 is a top plan view thereof;

FIG. 4 is a bottom plan view of a first and third embodiment of a canister, showing a cap portion independent of the canister to show aspects of the design not visible when combined;

FIG. 5 is a side and bottom perspective view of a second and fourth embodiment of a canister, showing a cap portion independent of the canister to show aspects of the design not visible when combined;

FIG. 6 is a bottom plan view thereof;

FIG. 7 is a bottom plan view of a first, second, third, and fourth embodiment of a canister;

FIG. 8 is a side perspective view of a first and second embodiment of a canister shown in an assembled configuration with the cap portion;

FIG. 9 is an exploded side perspective view of a first embodiment of a canister;

FIG. 10 is a front elevation view of a first and second embodiment, shown in an assembled configuration with the cap portion, wherein the back, left and right side views are identical;

FIG. 11 is a top plan view of a first, second, third, and fourth embodiment of a canister;

(Continued)

FIG. 12 is a front perspective view of a first and second embodiment of a canister, shown with the cap removed to show aspects of the design not visible when combined; FIG. 13 is a front elevation view of a first and second embodiment of a canister thereof, wherein the back, left, and right side views are identical;

FIG. 14 is a front, top perspective view of a third and fourth embodiment of a canister, shown in an assembled configuration with the cap portion;

FIG. 15 is a front elevation view of a third and fourth embodiment of a canister, wherein the back, left, and right side views are identical;

FIG. 16 is a top perspective view of a third and fourth embodiment of a canister, shown with a cap removed to show aspects of the design not visible when combined;

FIG. 17 is an exploded side perspective view of a third embodiment of a canister;

FIG. 18 is a front elevation view of a third and fourth embodiment of a canister, shown with a cap removed to show aspects of the design not visible when combined, wherein the back, left, and right side views are identical; and,

FIG. 19 is a top plan view of a first, second, third and fourth embodiment of a canister, shown with a cap removed. There are two kinds of broken lines in the drawings: The uniformly broken lines in the drawings represent portions of the canister that form no part of the claim. The broken lines shown as two short dashes and a longer dash represent symbolic breaks that form no part of the claimed design. Any portion of the article in between the break lines forms no part of the claimed design.

1 Claim, 15 Drawing Sheets
